UNITED STATES PATENT OFFICE.

JOHN MILFORD MOORHOUSE, OF WINNIPEG, MANITOBA, CANADA.

AEROPLANE.

1,176,084.

Specification of Letters Patent. Patented Mar. 21, 1916.

Application filed May 14, 1914. Serial No. 838,520.

To all whom it may concern:

Be it known that I, JOHN MILFORD MOORHOUSE, a subject of the King of Great Britain, of the city of Winnipeg; in the 5 Province of Manitoba, Canada, have invented certain new and useful Improvements in Aeroplanes, of which the following is the specification.

The invention relates to an aeroplane particularly to the biplane class and the objects of the invention are to provide an adjustable top plane which can be adjusted for ascending or descending purposes and which can be banked against the bottom plane to 10 present a large air resisting surface and arrest a downward plunge of the machine; to supply adjustable ailerons at the ends of the bottom plane; to provide a stability plane located above the center of gravity point of 15 the machine; and to provide an improved form of steering device comprising independently mounted vertical and horizontal rudders controlled by a single hand wheel either independently or together.

With the above objects in view the invention consists essentially in the arrangement and construction of parts hereinafter more particularly described and later pointed out in the appended claims.

Figure 1 is a side view of the complete machine. Fig. 2 is a plan view of the same. Fig. 3 is an enlarged detailed side elevation of a portion of the fuselage showing the aviator's seat and controlling wheels adjoining the same. Fig. 4 is a plan view of the parts shown in Fig. 3.

In the drawings like characters of reference indicate corresponding parts in each figure.

1 represents the fuselage or main body of the machine which comprises four principal struts 2 passing lengthwise of the machine and connected by suitably spaced cross braces or stays 3.

4 and 5 are pairs of upright standards permanently secured to the fuselage forwardly and having their upper ends connected and their lower ends spaced apart and secured to skids 6 and 7.

8 represents the bottom plane carried by a suitable rectangular frame-work 9 permanently connected to the fuselage in any suitable way. It is to be noticed that the plane is open above the fuselage this allowing of 55 the various levers and hand wheels later referred to.

The frame-work of the main plane comprises two centrally disposed struts 10 and 11, pairs of front and rear struts 12 and 13 and cross pieces 14 connecting the struts, the 60 forward strut 12 being fastened to the main frame by a bar 15. The plane is suitably trussed by stay wires.

16 and 17 are pairs of upright standards extending above the main frame and carried 65 by the struts 10 and 11, which standards are also suitably braced by stay wires passing between the standards and the plane.

18 is a top plane carried by a suitable frame-work 19, comprising front and rear 70 struts 20 and 21 and cross pieces 22 connecting the struts. Pivot pins 23 support the top plane from the standards 16 and 17 and a cross bolt 24 secures the top plane centrally and pivotally to the upper ends of the 75 standards 4 and 5 which it will be noticed extend above the bottom plane practically the same distance as the standards 16 and 17.

25 is a cross shaft mounted in suitable bearings carried by the framework of the 80 main plane and 26 and 27 are sprocket wheels fixed on the ends of the shaft and protruding through the bottom plane.

28 and 29 are bowed rack bars permanently secured to the top plane and provided 85 each with a series of openings 28' and 29' arranged to receive the teeth of the wheels 26 and 27. The rack bars are held in engagement with the teeth on the cross shaft.

32 represents the aviator's seat located on 90 the main frame and 33 is a hand wheel located adjoining the seat and carried by a short stub shaft 34 supplied with a chain wheel 35 connected through a chain 36 with a chain wheel 37 fixed on the shaft 25. 95

The aviator can swing the top plane by turning the hand wheel 37 to rotate the shaft 25 which shaft in turn swings the rack bars, the teeth of the sprocket wheels 26 and 27 entering the openings 28' and 29' respectively. The inner end of the stub shaft is mounted on a suitably located bar 38.

39 is a bearing plate secured permanently to the under side of the fuselage and carrying a rotatably vertically disposed spindle 105 40 connected through a universal joint 41 with the lower end of a steering post 42 provided at the top with a steering wheel 43, this wheel being located immediately forward of the aviator's seat.

A guide bar 44 passes between the aviator's seat and the strut 11, this bar and the

bar 38 forming a guide way which receives the steering post and prevents it from being moved laterally but allows it to swing forwardly and rearwardly.

5 The lower end of the spindle 40 is fitted with a cross-head 45 to which I have connected two crossed wires 46 and 47 which pass rearwardly to a steering bar 48 permanently secured to the lower end of a vertically directed bolt 49 pivotally mounted in suitable bearing plates 50 located at the rear end of the fuselage.

10 51 is a vertical rudder permanently secured to the bolt 49. The rudder is reinforced by stay wires 52 passing from the sides thereof to the steering bar. It is particularly to be noticed that the rudder is shaped more or less in the form of the tail of a fish.

15 20 Immediately to the rear of the aviator's seat I have located a pivot or rocking lever 53 which is connected to the steering post by a coupling bar 54, the rear end of the bar being fastened to the lower end of the 25 rocking lever.

30 55 is a permanent stability plane normally in the same plane as the top plane and supported by pairs of uprights 56 and 57 secured to the fuselage. The forward end of 35 the stability plane is contracted and anchored or fastened to the cross bolt 24, the top plane being cut away at 58 to admit it. The rear or wide end of the stability plane is reinforced by stay wires 59 passing over 40 a truss 60 located on the top of the stability plane and tied to the plane and to the fuselage. Details of this construction are not entered into as any suitable manner of bracing can be used.

45 40 61 is a horizontal rudder hinged at 62 to the rear end of the stability plane. The rudder carries centrally an upwardly directed bracket 63' and a downwardly directed bracket 63 which brackets are connected by cables or wires 64 and 65 with the ends of the rocking lever 53.

50 According to the construction hereinbefore disclosed it will be seen that one can get any of the three movements of the 55 rudders now given. 1st. He can swing the vertical rudder without moving the horizontal rudder by simply turning the hand wheel. 2nd. He can manipulate the horizontal rudder without moving the vertical rudder by 60 swinging the steering post forwardly or backwardly in the guide way. 3rd. He can manipulate both rudders together by turning the hand wheel and at the same time swinging the steering post forwardly or backwardly.

65 66 and 67 are ailerons pivotally secured at 68 to the ends of the main or bottom plane. The ailerons carry upwardly extending brackets 69 which are connected one to the other by a cross rod 70 extending above the

main plane. A turn-buckle 71 is inserted in the rod for adjusting purposes.

72 is a horizontally disposed control lever secured at 72' to a quadrant 72² permanently fastened to the framework of the main plane. The lever is connected to the cross rod by a pin 73 carried by the rod, the pin operating in suitable slots formed in the lever and a strap 74 carried by the lever. The lever is fitted with a hand latch 75 and 75 detent 76 the detent operating over the quadrant. The control lever extends backwardly within convenient range of the aviator's seat so that he can dip the ailerons at will by swinging the lever in one direction or the other.

77 represents an engine mounted in the forward end of the fuselage and 78 a propeller mounted on the engine shaft 79.

80 80 are landing wheels rotatably mounted 85 in the ends of a cross axle 81 carried by the skids.

It is to be noticed that the stability plane is located above the fuselage and aviator's seat, that is, above the center of gravity 90 point of the machine and that it is located farther in the same plane as the top plane so that a large air resisting area is exposed. I wish also to call attention to the adjustable feature of the top plane. This adjusting 95 feature is particularly useful when the aviator wishes to descend as he can retard the machine in its downward flight by swinging the top plane until its rear edge 100 rests against the bottom plane. This exposes a large resisting area to the air entrapping it between the planes.

What I claim as my invention is:—

1. In an aeroplane the combination with a fuselage, a horizontally disposed main plane mounted on the fuselage, a horizontally disposed stability plane elevated above the fuselage, a horizontally disposed rudder pivotally connected to the rear end of the stability plane and a vertically disposed rudder pivotally connected to the rear end of the fuselage, of a rotatably mounted spindle carried by the fuselage and provided with a cross head suitably connected with the vertically disposed rudder, a steering post connected with the spindle by means of a universal joint and provided with a suitable hand wheel, a rocking lever carried by the fuselage to the rear of the steering post, a suitable connection between the rocking lever and the horizontally disposed rudder, a coupling bar connecting the rocking lever with the steering post and guide bars carried by the fuselage and forming a guide way for the steering post, said bars being arranged to prevent lateral movement of the steering post, as and for the purpose specified.

2. In an aeroplane the combination with a fuselage and a main horizontally disposed

plane mounted forwardly on the fuselage, and extending transversely across the same, of a horizontally disposed, longitudinally directed stability plane elevated above the 5 fuselage and having the forward end thereof contracted and the rear portion thereof gradually increasing in width in passing backwardly, the forward end of said stability plane being disposed centrally above 10 the main plane and a transversely extending, normally horizontally disposed adjustable top plane superimposed above the main plane and having a portion of the rear side thereof cut away to admit the contracted 15 forward end of the stability plane.

3. In an aeroplane the combination with a fuselage and a main horizontally disposed plane mounted forwardly on the fuselage, and extending transversely across the same, 20 of a horizontally disposed, longitudinally

directed stability plane elevated above the fuselage and having the forward end thereof contracted and the rear portion thereof gradually increasing in width in passing 25 backwardly, the forward end of said stability plane being disposed centrally above the main plane, a transversely extending, normally horizontally disposed adjustable top plane superimposed above the main 30 plane and having a portion of the rear side thereof cut away to admit the contracted forward end of the stability plane and a horizontally disposed rudder pivotally connected to the rear end of the stability plane. 35

Signed at Winnipeg this 6th day of August, 1913.

JOHN MILFORD MOORHOUSE.
